United States Patent

Des. 237,751
Patented Nov. 18, 1975

237,751

LAUNDRY BAG

Michael C. Wilson and Leslie E. Schnick, Wheaton, Ill.,
assignors to Pretty Products, Inc., Coshocton, Ohio

Filed Jan. 15, 1974, Ser. No. 433,553

Term of patent 14 years

Int. Cl. D3—02

U.S. Cl. D87—1

FIG. 2

FIG. 1

FIG. 3

FIG. 4

FIG. 5

FIG. 1 is a rear elevational view of a laundry bag showing our new design;

FIG. 2 is a side elevational view thereof as seen on the right of FIG. 1;

FIG. 3 is a fragmentary sectional view on an enlarged scale taken along line 3-3 of FIG. 1;

FIG. 4 is a front elevational view thereof on an enlarged scale with a portion of the bag removed; and

FIG. 5 is a horizontal sectional view taken along line 5-5 of FIG. 4.

I claim:

The ornamental design for a laundry bag, substantially as shown and described.
